United States Patent Office

Des. 183,098
Patented June 24, 1958

183,098

COMBINED RAZOR AND BLADE RECEPTACLE

Paul Jacobs, Bronx, N. Y.

Application April 8, 1957, Serial No. 45,639

Term of patent 3½ years

(Cl. D4—3)

Fig. 1 is a front perspective view of a combined razor and blade receptacle, showing my new design;

Fig. 2 is a rear elevational view;

Fig. 3 is a side elevational view; and

Fig. 4 is a top plan view of the same.

I claim:

The ornamental design for a combined razor and blade receptacle, as shown.
